UNITED STATES PATENT OFFICE.

ANDREAS LOCK, OF HAMBURG, GERMANY.

CARRIAGE MOVEMENT FOR TYPEWRITERS.

Application filed July 22, 1924, Serial No. 727,573, and in Germany July 28, 1923.

This invention relates to escapement mechanism for controlling the movement of the typewriter platen carriage in front stroke typewriting machines in which the movement or spacing is produced by means of a double-armed lever which is struck by the type bars near the printing point.

In well-known devices of this kind, the movement or spacing of the carriage is brought about by the double-armed lever which is controlled by the type-bars, engaging by means of two pawls or dogs with a spring member mounted on a spindle and rotating the said member with the spindle, owing to which a worm secured to the bottom end of the spindle produces a rotation of the worm wheel engaging with the said worm and with the spacing wheel.

My invention has for its object to provide an improved mechanism for transmitting the movement of the double-armed lever actuated by the type bars to the dog-rocker which controls the escapement wheel and thereby the movement of the platen carriage.

The invention has the advantage that the path described until the escapement wheel is released, is considerably shortened, owing to which a quick and reliable spacing is ensured.

A further advantage of the invention is that it enables a much more compact arrangement of the parts to be attained than has hitherto been possible since, in the new device, two small straight levers which take up little space are used and the dog-rocker and escapement wheel are situated behind the said levers.

In addition to its simplicity and the greatest possible reliability, the invention has the advantage over the well-known devices that the well-known noise and clatter of the escapement mechanism is reduced to a minimum.

Furthermore, the new device can be used for typewriters with simple change of spacing.

My invention consists essentially in the features of construction, arrangements of parts, and combinations of devices to be hereinafter described and particularly pointed out in the appended claims.

A construction according to the invention is illustrated by way of example in the accompanying drawing in which Fig. 1 shows the typewriter with the escapement

device and carriage moving mechanism, with the segment partly broken off, in elevation. Fig. 2 is a plan of the same with the platen partly broken off. Fig. 3 is a front elevation of the typewriter to which the invention has been applied. Fig. 4 shows the escapement device with parts of the carriage support in plan. Fig. 5 shows the same in side elevation and Fig. 6 in front elevation.

The type bars 3 connected to the key levers 1 by means of levers 2, engage with slots in the segment 4 and are held by the through bearing pin 5. At the front side of the segment, in the center of the same is mounted the type guide 6 which is secured to the segment by screws. To the back surface of the segment, also in the centre of same, is secured by screws a bearing block 7. In the said bearing block are mounted two double levers (viz, a double-armed universal lever 12, 14 and a double-armed intermediate lever 15, 16) engaging with each other and held in the bearing blocks by means of bearing pins 10, 11 passing through the collar on the spindle of the levers. The upper arm 12 of the upper lever carries at its end a buffer 13 of elastic material which is arranged transversely of the lever arm, passes through a corresponding recess in the type-guide and forms an abutment for the type-levers. The lower arm 14 of the upper lever is formed into a tongue and engages with the arm 15—also formed into a tongue—of the lower lever. The arm 16 of the lower lever rests against an angle stop 17 of the pawl support.

In addition to the double-armed lever 15, 16, with the pawl support engages also a double-armed lever 20 connected to the line spacing key 19. The lever 20 is rotatably mounted by means of its collar in an angle bracket 21 and held by means of a pin 22. The angle bracket 21 is secured by screws to the carriage support 23. The pawl support 18 rests on a bracket 24 mounted on the carriage support 23 and is pivoted to it about screwbolts 25.

On the pawl support are arranged side by side two pawls 26, 27 which are used for locking or releasing the escapement wheel. Of the said pawls, the pawl 26 is secured to the pawl support by means of rivets 28, whilst the pawl 27 is adjustably mounted on the pawl support by means of a screw bolt 9. A tension spring 30 secured to the

carriage support 23 and to a pin 29 of the pawl support, is intended to bring the oscillating pawl support back to its closing position, whilst a pin 31 secured to the bracket 24 rests against the edge of the pawl support and guides it in a positive manner.

In the position of rest, the escapement wheel 32 is in engagement with the movable pawl 27. The escapement wheel 32 as well as the gear wheel 33, are mounted on a spindle 34 supported in the carriage support. The wheel 33 engages with the rack 35.

The carriage is held in a cocked position in a well known manner by means of a tension device.

The working of the new device is as follows:

The movement of the key lever 1 produces such a movement of the type bar 3 connected to it by means of the lever 2, that the said type bar, before striking the platen, strikes the buffer 13 of the double-armed lever 12, 14 thus communicating a pressing impulse to it, owing to which the lever 12, 14 which is connected to the pawl support 18 by means of the double-armed lever 15, 16 receives a pressing impulse and is turned, and the pawl support moved back, so that the pawl 27 adjustably mounted on the pawl support, is disengaged from the escapement wheel 32 which is thus released. The pawl support 18, and with it the universal lever 12, 14 and the intermediate lever 15, 16 are thereupon returned to their original position by the tension spring 30.

What I claim is:—

1. In a front-stroke typewriting machine provided with type bars, an escapement mechanism for controlling the movement of the platen carriage, comprising in combination a double-armed universal lever adapted to be operated at its upper end near the printing point by any of the type bars, an intermediate double-armed lever adapted to turn about an axis parallel to and located below the axis of rotation of the first named universal lever and having its upper arm in contact with the lower arm of the universal lever, a spring actuated dog rocker arranged behind the lower arm of the intermediate lever and actuated by pressure exerted by the said lower arm, and an escapement wheel controlled by the said rocker, substantially as described.
2. In a front-stroke typewriting machine provided with type bars, an escapement mechanism for controlling the movement of the platen carriage comprising in combination a substantially straight double-armed universal lever turning about a horizontal axis and adapted to be operated at its upper end near the printing point by any of the type bars, a substantially straight intermediate double-armed lever adapted to turn about a horizontal axis and located below the axis of rotation of the first named universal lever and having its upper arm in contact with the lower arm of the universal lever, said universal and intermediate levers lying in one vertical plane, a spring actuated dog rocker turning about a vertical axis, said dog rocker being arranged behind the lower arm of the intermediate lever and actuated by pressure exerted by the said lower arm, and an escapement wheel adapted to turn about a horizontal axis and controlled by said rocker, substantially as described.

axis and adapted to be operated at its upper end near the printing point by any of the type bars, a substantially straight intermediate double-armed lever adapted to turn about a horizontal axis located below the axis of rotation of the first named universal lever and having its upper arm in contact with the lower arm of the universal lever, said universal and intermediate levers lying in one vertical plane, a spring actuated dog rocker arranged behind the lower arm of the intermediate lever and actuated by pressure exerted by the said lower arm, and an escapement wheel controlled by the said rocker, substantially as described.

3. In a front-stroke typewriting machine provided with type bars, an escapement mechanism for controlling the movement of the platen carriage comprising in combination a double-armed universal lever having at its upper end an elastic buffer and adapted to be operated at its upper end near the printing point by any of the type bars, an intermediate double-armed lever adapted to turn about an axis parallel to and located below the axis of rotation of the first named universal lever and having its upper arm in contact with the lower arm of the universal lever, a spring actuated dog rocker arranged behind the lower arm of the intermediate lever and actuated by pressure exerted by the said lower arm, and an escapement wheel controlled by the said rocker, substantially as described.

4. In a front-stroke typewriting machine provided with type bars, an escapement mechanism for controlling the movement of the platen carriage comprising in combination a substantially straight double armed universal lever turning about a horizontal axis and adapted to be operated at its upper end near the printing point by any of the type bars, a substantially straight intermediate double armed lever adapted to turn about a horizontal axis and located below the axis of rotation of the first named universal lever and having its upper arm in contact with the lower arm of the universal lever, said universal and intermediate levers lying in one vertical plane, a spring actuated dog rocker turning about a vertical axis, said dog rocker being arranged behind the lower arm of the intermediate lever and actuated by pressure exerted by the said lower arm, and an escapement wheel adapted to turn about a horizontal axis and controlled by said rocker, substantially as described.

In testimony whereof I have signed my name to this specification.

ANDREAS LOCK.
